UNITED STATES PATENT OFFICE

2,155,231

FAN AND METHOD OF MAKING SAME

Albert B. Hubbard and Myles Stanton, Bloomfield, N. J., assignors to General Electric Company, a corporation of New York

Application June 1, 1936, Serial No. 82,821

14 Claims. (Cl. 29—156.8)

Our invention relates to a fan and more particularly to a fan construction and assembly.

An object of our invention is to provide an improved fan which is of low cost of manufacture and may be expeditiously assembled.

What we consider to be novel and our invention will be better understood by reference to the following specification and appended claims when considered in connection with the accompanying drawings, in which Fig. 1 is a perspective view of a double fan wheel embodying our improved construction; Fig. 2 is a perspective view of a single fan wheel; Fig. 3 is a perspective view of the hub and two fan blades; Fig. 4 is a side sectional view through the hub showing two of the blades assembled thereon; Fig. 5 is a side view of a double fan with parts cut away to show the assembled relationship; Fig. 6 is a detail sectional view of a part of the assembly; Fig. 7 is a sectional view of a single fan wheel; Fig. 8 is a detail end view of a part of the fan of Fig. 7, and Fig. 9 is a detail end view of the hub end of the fan of Fig. 7.

Referring to the drawings, 10 indicates a double fan wheel having a plurality of blades 11 extending axially from one side of a hub 12 and a plurality of blades 13 extending from the other side of the hub. Referring to Fig. 3, it may be seen that blades 11 have integral feet 14 and integral shroud ring sections 15. Similarly, blades 13 have feet 16 and shroud ring sections 17. Hub 12 has two annular grooves 18 and 19, as better indicated in Fig. 4. Feet 14 have projections 20 which extend into groove 18, and feet 16 have projections 21 which extend into groove 19. Feet 14 have segmental radial sections 22 which are in abutting relation with adjacent sections 23 and extend to engage one face of hub 12. Also, feet 16 are provided with segmental sections 23. The blades 11 and 13 are located alternately around the periphery of hub 12 and are secured to hub 12 by means of a wire binding 24 which is wound tightly over feet 14 and 16 overlying the periphery of hub 12. Adjacent turns of wire 24 are soldered together under predetermined tension to form a unitary binding structure. To prevent the wires 24 from unwinding before they are soldered, clips 25 are provided. If the fan wheels are rotated at a higher speed than their normal operating speed, there may be a tendency for the blades to stretch the binding wires 24 due to the centrifugal forces and thus become loose on the hub 12. In such a case the blades would tend to rotate or slide about the hub 12. To prevent relative movement be-

tween the blades 11 and 13 and hub 12, one of the blades is secured against relative rotary movement by means of a pin 26 which may be seen by reference to Figs. 4 and 6. With one of the blades secured to the hub 12 by means of pin 26, it is impossible for the other blades to move around the periphery of the hub so it is not necessary to secure each of the blades individually to the hub. To insure the proper fitting and positioning of the blades, the projections 20 and 21 are made somewhat smaller than the grooves 18 and 19 and the feet 14 and 16 are of such a length as to provide a clearance between their ends and the segmental sections 23 and 22 respectively of the blades 13 and 11. By this arrangement the binding wire 24 holds the blades 11 and 13 in tight engagement with the periphery of the hub 12 and with the segmental sections 22 and 23 in close engagement with the opposite faces of the hub 12. Shroud ring sections 15 and 17 nest together to form continuous shroud rings. Shroud ring section 15 is provided with projections 27 which extend into corresponding recesses provided in the adjacent shroud ring section 17. Similarly, shroud ring section 17 is provided with projections 28. To assist in securing the blades 11 and 13 together wire bindings 29 and 30 are wound around the shroud ring sections 15 and 17 respectively. Clips 31 and 32 are provided to prevent wires 29 and 30 from unwinding. In Figs. 5 and 6 it may be seen how the alternate feet 14 and 16 are mounted on the hub 12 and secured thereto by means of wire 24 and prevented from relative rotation by means of the pin 26. In Fig. 5 the relation of the shroud ring sections 15 with their projections 27 and securing means consisting of wire 29 serve to form a rigid structure. In Fig. 2 a single fan wheel is shown identical in construction to the right-hand fan wheel of Fig. 1, the same blades 13 being secured to hub 12. A space is thus left between the adjacent feet 16 but this does not affect the rigidity of the fan wheel as the segmental sections 23 are in abutting relation. In Figs. 7, 8 and 9 a modified construction of single wheel is shown. In this modified construction the blade 33 has a foot 34 which abuts the foot 34 of adjacent blade 33 substantially throughout its length so that only a single set of blades can be mounted on the hub 35. This form of construction is desirable for larger diameter fans. In Figs. 7 and 9 it may be seen that two projections 36 are provided on one side of foot 34 and one projection 36 on the opposite side. These projections 36 serve to space the blades 33 uniformly around the hub 35.

- periphery of hub 35 and distribute the clearance which must be provided in the blade assembly between adjacent blades to allow for some variation or tolerance in the blade widths. When the blades 33 are secured to the hub 35 by means of binding wire 37 the projections 36 are crushed until the foot 34 tightly embraces the outer periphery of hub 35 and distributes the clearance between the feet 34 equally among the blades 33.
10. In the manufacture of the fan wheel, the hub 12 is cast and machined and the blades 11 and 13 are cast with the integral feet 14 and 16 and shroud ring sections 15 and 17. The blades 11 and 13 are then mounted around the periphery of hub 12, one of the blades being secured to the hub by means of a pin 26. The blades 11 and 13 are then clamped to the hub 12 with the faces of segmental sections 22 and 23 abutting opposite faces of the hub 12. The wire 24 is then secured at one end and wound under a predetermined tension around the feet 14 and 16, the clips 25 being inserted as the wire progresses around the periphery of hub 12. A tinned phosphor bronze or stainless steel wire 24 is used so that when the winding operation has been completed the adjacent turns may be readily soldered together. The clips 25 are turned down before the adjacent turns are soldered. The tension which is used is determined by the normal operating speed of the fan and is made such that it will resist the centrifugal forces at such speed so the fan blades will not become loose on hub 12. At a higher speed the wire will stretch sufficiently to cause the blades to loosen. If this predetermined tension were not used then the blades would begin to loosen on the hub 12 as soon as the wheel began to rotate. The wire 24 may be wound around the feet 14 and 16 either by rotating the wheel or by rotating the winding means. The wire bindings 29 and 30 and clips 31 and 32 are then put on in the same manner as binding 24. The assembly of the single wheels of Figs. 2 and 7 is the same as the assembly of the double wheel as above described. After the 45 wheels have been assembled, it is necessary to balance them. The positions at which weights must be located are first determined. In the case of the double wheel of Fig. 1 the weights are applied on the wire bindings 29 and 30 of shroud ring sections at 38 and 39 in the form of solder. The solder is flowed on the wire bindings 29 and 30 in a practically uniform layer and the length of wire over which the solder is applied determines the weight that is being added at this 55 point. The single wheel of Fig. 2 is similarly balanced by the application of weights in the form of solder to the wire bindings 24 and 30 at 40 and 41 respectively. Thus in the case of the single wheel the weights are added at the hub 60 and at the shroud ring sections. In this manner the balancing of the wheels is accomplished accurately with greater facility than could be possible by the addition of other weights at different locations.
65. From the foregoing it may be seen that the fan wheel is formed of a minimum number of integral parts which are assembled and rigidly secured together in a simple and expeditious manner.
70. What we claim as new and desire to secure by Letters Patent of the United States is:
1. In combination, a hub, fan blades extending axially from the hub and having abutting portions overlying the periphery of the hub and a wire wound over the abutting portions of the
  2. In combination, a hub, fan blades extending axially from the hub and having portions abutting the face of the hub and each other and other portions overlying the periphery of the hub, and a wire wound over the portions overlying the periphery of the hub to secure the blades to the hub.
  3. In combination, a hub, fan blades extending axially from the hub and having portions overlying the periphery of the hub, a wire wound over the portions of the blades overlying the periphery of the hub to secure the blades to the hub, and clips securing the adjacent turns of 15 wire together to prevent them from unwinding.
  4. In combination, a hub, fan blades extending axially from the hub and having portions overlying the periphery of the hub, and wire wound over the portions of the blades overlying the periphery of the hub to secure the blades to the hub, the adjacent turns of said wire being soldered together.
  5. In combination, a hub, fan blades extending axially from the hub and having shroud ring sections which when assembled form a substantially continuous ring, and integral feet, said feet overlying the periphery of the hub, and wire wound over the feet to secure the blades to the hub.
  6. In combination, a hub, fan blades extending axially from the hub and having integral feet and shroud ring sections, said feet overlying the periphery of the hub, wire wound over the feet to secure the blades to the hub, and wire wound over the shroud ring sections to more rigidly secure the blades together.
  7. In combination, a hub, fan blades extending axially from the hub and having portions overlying the periphery of the hub, a wire wound under tension over the portions of the blades overlying the periphery of the hub to secure the blades to the hub, and a pin securing one of said blades to the hub to prevent relative rotary movement between the blades and hub.
  8. In combination, a hub, fan blades having integral feet and shroud ring sections, said feet overlying the periphery of the hub, segmental sections of said feet abutting the feet of adjacent blades and having projections to distribute the clearance between blades equally among the blades, and a wire wound under tension over the feet to secure the blades to the hub.
  9. In combination, a hub, fan blades extending alternately in an axial direction from opposite sides of the hub having portions overlying the periphery of the hub, and a wire wound over the portions of the blades overlying the periphery of the hub to secure the blades to the hub.
  10. In combination, a hub, fan blades extending from one side of the hub having integral feet and shroud ring sections, fan blades extending from the opposite side of the hub from said first mentioned fan blades and having integral feet and shroud ring sections, the feet of said fan blades extending from opposite sides and located alternately around the periphery of the hub, a pin securing one of said blades to the hub, a wire wound over the feet of all the fan blades to secure the blades to the hub, and additional wires wound over the shroud ring sections of the blades extending from both sides of the hub to more rigidly secure the blades together.
  11. The method of manufacturing a fan wheel which consists in mounting the fan blades on the

hub and extending axially therefrom with a portion overlying the periphery of the hub, clamping the fan blades to the hub, winding a wire under tension over the portion of the blades overlying the periphery of the hub, and soldering the adjacent turns of wire together.

12. The method of manufacturing a fan wheel which consists in mounting blades having foot members on a hub with the foot members overlying the outer periphery of the hub, clamping the fan blades to the hub, securing one of the fan blades to the hub against relative rotary movement by means of a pin, winding a wire over the foot members under tension, inserting clips as the wire is wound over the foot members, turning the clips down to prevent unwinding of the wire after the winding operation has been completed, and soldering the adjacent turns of wire together.

20 13. The method of manufacturing a fan wheel

which consists in mounting fan blades having foot members and shroud ring sections on a hub, clamping the fan blades on the hub with the foot members overlying the outer periphery of the hub and the shroud ring sections of adjacent blades abutting, pinning one of the blades to the hub to prevent relative rotary movement between the blades and hub, winding a wire binding under tension over the foot members, soldering adjacent turns of wire together, winding a wire 10 binding over the shroud ring sections under tension, and soldering the adjacent turns of wire of the last mentioned binding together.

14. In a fan, axially extending blades having abutting sections providing a shroud ring, and tension means wrapped around said sections and exerting a compressive force toward the axis of the fan securing the blades together.

ALBERT B. HUBBARD.
MYLES STANTON.
